Specification of Letters Patent.

Patented May 9, 1916.

Application filed May 25, 1914. Serial No. 840,789.

To all whom it may concern:

Be it known that I, HENRY A. HENTRICHES, a citizen of the United States, residing at Newark, in the county of Essex and 5 State of New Jersey, have invented certain new and useful Improvements in Registers, of which the following is a specification, reference being had therein to the accompanying drawings.

10 This invention pertains to a system in which there are a plurality of primary or local adding and registering machines and a grand-totalizer adding and registering machine. Every primary machine is oper- 15 able from any suitable distance to add amounts and register totals, and it includes means whereby its amounts, along with those of other primary machines, are caused to be added in the grand totalizer, which 20 shows the grand total of all primary machines.

The system and the mechanisms included in it may be put to various uses, as, for example, to add and register the values received at the admission-ticket-selling stations of a base-ball or other amusement park, at the various ticket-selling stations in an amusement-park, or at the various selling-stations in a department store, and 25 thus they make available at any time information as to the amount of sales or values received at every such station and the total of all stations.

The invention contemplates, in both primary and grand-totalizer machines, the provision of means for causing actuation of the registering mechanisms so arranged as to avoid under registration when initial movements for effecting registration of a 30 plurality of the same units are made simultaneously at one or more places; and it provides in a primary machine means whereby the amounts registered therein are caused also to be registered in a grand-totalizer ma- 35 chine.

When read in connection with the description herein, the characteristics of a system and of its component parts as contemplated by the invention, and the im- 40 provements made therein by the invention, will be apparent from the accompanying drawings, forming part hereof, wherein are shown, for purposes of illustration, a system and mechanisms adapted for use in a 45 department store or the like.

While the disclosures herein now are considered to exemplify preferable embodiments of the invention it is to be understood that the invention is not restricted in its uses or adaptations to those described 60 and shown, and that the showing herein may be altered and otherwise adapted within the scope of the claims without necessarily departing from the nature and spirit of the invention. 65

Like reference-characters refer to corresponding parts in the views of the drawings, of which—

Figure 1 is a transverse sectional view through a portion of a primary or local 70 machine; Fig. 2 is a detail view in elevation of a ball-releasing device; Fig. 3 is a detail plan view of parts of a ball-releasing device; Fig. 4 is a plan view, partly in section and with certain parts omitted, of mag- 75 azines and other parts, some of which are shown in elevation by Fig. 1; Fig. 5 is a view of gearing for actuating the chain- 80 belts; Fig. 6 is a view of guideways as seen when looking in direction of the arrows, Fig. 1, one of the guideways being shown in elevation and the other in section; Fig. 7 is a plan view of an alternative arrangement of ball-channels and release me- 85 chanisms therefor; Fig. 8 is a view in eleva- 85 tion and partly in section of parts shown by Fig. 7; Fig. 9 is a rear view, partly in section, of a series of number-displaying 90 dials and parts associated therewith; Fig. 10 is a plan view of parts shown by Fig. 9; Fig. 11 is an enlarged sectional view of 90 parts associated with dials; Fig. 12 is a dia- 95 grammatic view of a system contemplated by the invention; and Fig. 13 is a view illustrative of the diverse arrangement of teeth of the chain-belts.

For purposes of brevity and clearness, the circuit-closers and the like, the parts whose actuation they institute, and electric conductors connecting parts are referred to by 100 the number of units of which it is intended for them to cause registration. For example, "forty-unit circuit", "forty-unit conductor", "forty-unit magazine", "forty-unit channel", "forty-unit balls", "forty-unit 105 guideway", and "forty-unit star-wheel" all refer to parts contributing to registration of forty units, as forty cents or forty dollars.

In the adaptation of one of the systems herein contemplated as shown by Fig. 12 110

as an example, there are a plurality of departments, selling-places, groups, or classes A, B, C, in each of which there are electric contact keyboards, sets of circuit-closers, or 5 individual circuit-closers, *a*, *b*, *c*, *d*, *e*, etc., corresponding in number to the number of selling or dispensing stations, to the number of clerks or others, or to the number of places in a group or class at which registrations 10 are to be initiated, it being understood that these keyboards, sets of circuit-closers, or individual circuit-closers, only are exemplary of any suitable circuit-closing devices, such as mechanisms associated with 15 cash-registers or the like. For every department, group, or class of circuit-closers at which registrations are to be initiated, there is in a central office or the like, which may be located at any practicable distance, 20 a primary or local adding and registering machine A', B', or C', as the case may be, each of which is connected electrically with, and arranged to add and register the amounts indicated at the keyboards, sets 25 of circuit-closers, or individual circuit-closers of its department, group, or class. Every primary or local machine is connected electrically with a grand-totalizer machine T and arranged to cause to be added and 30 registered therein the total amounts or values registered.

For all keys or circuit-closers of like-indicating amount of a single department, group, or class, there is in the primary or 35 local machine of that department, group, or class, one or more magazines M; and it may be assumed, for purposes of explanation, that the magazine at the left of Fig. 1 pertains to the forty-unit keys or circuit- 40 closers and the magazine at the right of that figure to the one-hundred-unit keys or circuit-closers, that there are five keyboards or sets of circuit-closers in that machine's department, group, or class, that five forty-unit electric conductors 40^x lead therefrom 45 in circuit to devices associated with the forty-unit magazine, that five one-hundred-unit electric conductors 100^x lead in circuit from the keyboards or sets of circuit-closers 50 to devices associated with the one-hundred-unit magazine, and that conductors similarly lead from all other amount keys or circuit-closers to devices associated with other magazines in the machine.

55 In the framework of a primary machine there are mounted near each side an upper shaft 13 and a lower shaft 14, one of which is a drive-shaft, and on these shafts there is a plurality of sprocket-wheels 15, 60 those of the drive-shaft being fast thereon and those of the other shaft being mounted to rotate with it if it is rotatable and on it if it is fast. Every sprocket-wheel on an upper shaft is directly above a similar wheel 65 on the shaft below it, and every pair of

wheels is engaged by a chain-belt 16, which has bifurcated teeth or other projections 17 extending outwardly therefrom at regular intervals. The shafts extend longitudinally of the machine, and the drive-shafts are so 70 associated with each other that they will be rotated synchronously in opposite directions and move the inside or facing stretches of the chain-belts upwardly. In the embodiment shown, the lower ones are the drive-shafts, and they are rotated constantly and uniformly while the machine is in use by a main shaft 18 through the instrumentality of gears 19.

One of the magazines M is located in the 80 upper portion of the machine adjacent to every chain-belt 16, and leading downwardly therefrom there is a series of channels 20 corresponding in number to the number of keys or circuit-closers of the amount to 85 which the magazine pertains in the department, group, or class. The magazine is arranged to hold and to feed into its several channels 20 in series a number of amount-representing and register-actuating 90 elements 21, which preferably are of spherical form, and which hereinafter are called "balls".

For every channel there is a solenoid-coil 22, which is in the circuit of the circuit-closer of the amount to which the magazine pertains, and which is arranged to actuate a latch to release a ball from the channel. For example, the coils at the left of Fig. 1 are assumed to be connected each to a forty-unit conductor, and those at the right of that figure each to a one-hundred-unit conductor; and, when the circuit in one of these conductors is closed at a distant station, a ball will be released from a forty-unit or a one-hundred-unit channel, as the case may be, and it will be available subsequently to cause registration of that amount and addition to previously-registered amounts.

The latch referred to comprises a substantially vertical rock-shaft 23, having at its lower end a laterally-extending release-arm 24, which normally is held in the path of movement of the balls in the channel by an arm 25 on the shaft kept against a stop 26 by springs 27. An operating-arm 28 on the shaft is connected with a longitudinally-movable core 29 of the coil, and the relative arrangement of the parts is such that, when the coil is energized by closing the circuit in the conductor connected with it, the arm 28 will be moved under the influence thereof and release-arm 24 will be swung out of the path of the balls and a ball permitted to drop from the channel. In order to prevent the release of more than one ball when the release-arm 24 has swung to releasing position, there extends from the shaft 23 a stop-arm 30, which is positioned 110

above the release-arm a distance about equal to the diameter of the balls. The stop-arm is capable of swinging into the path of the balls within the channel, and it is so disposed with respect to the release-arm that it will swing into the channel under the next-to-the-bottom ball as the release-arm swings from under and releases the bottom ball. A fixed abutment 31 stops movement of the parts when the stop-arm has reached holding position. Of course, the circuit is closed for a moment only; and, when the circuit is opened, the parts will be returned to normal positions by the springs, the balls within the channel dropping down as the stop-arm moves outwardly thereof and being caught by the release-arm as it quickly returns to position in the path of the balls.

When the balls are released from the channels, each representing an amount of the denomination to which its mechanism pertains, as five units, ten units, forty units, one hundred units, and so on, as the case may be, they drop into a hopper 32 therebelow, from the bottom of which leads a chute 33, which is of a size to receive the balls in sequence and to hold them in series until they are taken up individually and successively by the teeth of the chain-belt, as now will be explained.

The chute leads at its lower end into the lower end of a guideway 34, which extends along the upwardly-moving stretch of the chain-belt, and which at its upper end projects into and somewhat above the bottom of the magazine M. The guideway at its bottom has a slot 35 and in its side abutting the chain-belt a longitudinal slot 36, these slots permitting the teeth 17 of the chain-belt to pass and extend into the guideway and to move upwardly therethrough. The guideway is just of sufficient size to permit one ball at a time to pass into it from the chute 33. If there is a ball within the guideway at the bottom at a time a tooth 17 passes into it during the continuous movement of the chain-belt, it is engaged by the tooth and moved upwardly through the guideway, to its top, whence it falls into the magazine where it again is available to pass into a channel and again be used as just described. If there are other balls in the chute, and possibly there may be a number there during busy times, each passes into the guideway as the ball preceding it is moved upwardly, and it is moved upwardly by the succeeding tooth of the chain-belt when it reaches ball-engaging position. Thus all balls as they are dropped into the hopper and pass to the chute successively are moved upwardly through the guideway by the belt-teeth and returned to the magazine, and no matter how many balls simultaneously

may be dropped into the hopper, each is carried separately through the guideway and made individually to perform registering and adding functions as yet to be described, whereby there is avoided such under registrations as might occur if certain registering mechanisms were operated simultaneously.

In order to make positive the removal of balls from the teeth 17 as they move above the upper end of the guideway, a member 37, preferably of sheet material, sufficiently narrow to permit the bifurcated teeth to straddle it, extends upwardly from that end of the guideway and curves slightly from the chain-belt. It is connected at its lower end to the guideway and at its upper end it is connected to and supported by the top of the magazine M, between which places of connection the teeth depart from a straight upward course of movement as the chain-belt passes onto the upper sprocket-wheel. The balls, if they already have not fallen off the teeth, will be combed off by member 37 as the teeth withdraw therefrom.

During upward movement in the guideway, each ball engages and operates certain devices that are arranged to cause actuation of registering mechanisms and that extend into the guideway through a slot 38 in the side opposite to the chain-belt. One of these devices is a rotary member or star-wheel 39, the arms or teeth of which are so proportioned and spaced that one of them always extends into the guideway in a position to be engaged by a ball, whereby the wheel is given a turn as the ball moves upwardly. Another of these devices is an electric circuit-closer that includes a pivoted arm 40, having on its free end a projection, such as a roller 41, which is capable of extending through the slot 38 into the path of the balls in the guideway. The arm 40 has thereon an extension 42 projecting oppositely from the roller 41. This extension has an insulated end in contact with a terminal 43 of an electric circuit, which is pivotally mounted at one end and normally held out of contact with another terminal 44 of the same circuit by a spring 45. The spring, through the instrumentality of the pivoted terminal, operates to keep the roller 41 normally in the path of the balls in the guideway. When an upwardly-moving ball contacts with the roller, the roller is pushed outwardly of the guideway, the pivoted arm thereby is given a swinging movement, and the pivoted terminal 43 thereby is caused to contact with the fixed terminal 44, whereby the circuit is closed. As soon as the ball passes from contact with the roller, the arm 40 and the roller thereon are returned to normal position by spring 45 and the circuit is opened.

The bifurcated teeth of the chain-belt are

so formed that they straddle the arms of the star-wheel and the roller of the circuit-closer during their movement in the guideway, and, therefore, they do not of themselves contact 5 with and move those parts, movement thereof only being imparted when there is a ball on a tooth.

In the grand-totalizer machine, there are ball-holding magazines, one or more for all 10 the magazines of the several primary or local machines of like value in the system, and each of the grand-totalizer magazines has associated therewith ball-releasing devices connected by conductors 46 with the 15 terminals 43 and 44 pertaining to magazines of like value in the primary machines. Thus, for example, when the circuit-closer of any forty-unit magazine, as assumed to be shown at the left of Fig. 1, is moved to close the 20 circuit at terminals 43 and 44, a ball of corresponding amount is dropped into the hopper of the grand-totalizer machine, after which it is moved to cause registration and addition of that amount by means like that 25 of a primary machine, such means as applied to the grand totalizer being exemplified in a primary machine and, therefore, it being unnecessary to duplicate its illustration and to repeat a description thereof.

30 In the diagrammatic outline of the system shown by Fig. 12, there are three primary machines, each having, among other magazines, one of forty-unit amount as typified at the left of Fig. 1 and one of one- 35 hundred-unit amount as typified at the right of that figure; and, therefore, there would be under the forty-unit magazine of the grand totalizer three channels whence balls are dropped and each controlled by a forty- 40 unit magazine of the primary machine, and under the one-hundred-unit magazine a like number of channels whence balls are dropped and each controlled by a one-hundred-unit magazine of the primary machine, and the 45 grand totalizer would contain other similar parts and associated mechanisms for the other amounts or units of the primary machines. In practice, probably there would be a greater number of primary machines 50 connected with and causing registrations in the grand totalizer, and sometimes possibly it would be necessary to provide more than one magazine of like value in a grand totalizer to accommodate all the circuit-closers of 55 that value in the primary machines.

While the ball-dropping-arrangements of the grand totalizer may be similar to those shown by Fig. 1 in a primary machine, for the purpose of illustrating a somewhat different ball-dropping arrangement that may be applied either to a primary or grand-totalizer machine to accommodate, respectively, a larger number of station circuit-closers or primary-machine circuit-closers

of the same value, there is shown by Figs. 7 65 and 8 another form of ball-dropping mechanism as adapted to a grand totalizer. In this form, the ball-containing channels 20 are arranged in a plurality of series under the magazine and above the hopper, and 70 each channel in a manner similar to the showing of Fig. 1 has pivoted adjacent thereto the latch rock-shaft 23, carrying the release-arm 24, the stop-arm 30, and the operating-arm 28. However, in order that the 75 channels may be placed closer together, the coils, instead of being located each adjacent to a channel, are disposed at the ends of the series of channels. Thus for every latch there is a coil 22, having therein the longitudinally-movable core 29 arranged to be 80 moved when the coil is energized and connected by a rod or link 47 with the latch operating-arm, whereby the rock-shaft is turned and the release and stop arms thereof operated as in the previously-described form. A spring 27 returns the parts to normal position.

It may be assumed, for purposes of explanation, that the ball-dropping arrangement shown by Figs. 7 and 8 pertains to forty-unit magazines of the primary machines, and that each coil thereof is connected by conductors 46 emanating from the forty-unit terminals of the primary machines. Therefore, when the circuit is closed at terminals 43 and 44 by movement of a circuit-closer as at the left of Fig. 1, a ball of corresponding amount will be caused to be dropped into the hopper of 100 like value of the grand totalizer and that value caused to be registered therein; and in the same manner balls will be caused to be dropped by the circuit-closers of other primary machines in the same hopper or 105 different hoppers of the grand totalizer, in accordance with the amount to which they pertain.

The teeth of all chain-belts in a primary machine and in a grand-totalizer machine 110 are so relatively arranged that only one of them in a single machine reaches position to cause a ball thereon to operate mechanism thereof at the same time, in order that there may be avoided simultaneous 115 movement of the ball-engaging star-wheels and a consequent under registration in the registering mechanism now to be described.

Adjacent to every star-wheel 39 there is a gear 48 mounted to be rotated by the 120 star-wheel, and these wheels and gears may be supported in any suitable manner, as on a shaft 49 extending along the series of guideways 34. The gears 48 on one side of the machine are in mesh with pinions 50 125 and those of the series on the other side are in mesh with pinions 51, the two series of pinions, respectively, being loosely mount-

ed on arbors 52 and 53, at the ends of which, respectively, are dials 52' and 53' carrying amount-indicating characters. The several meshing gears and pinions are relatively of 5 different sizes, dependent upon the amount of rotation to be given an arbor to cause it to effect registration of the amount to which may pertain a magazine with which a set comprising a star-wheel, gear, and pinion is 10 associated. For example, assuming that the magazine at the left of Fig. 1 contains balls each representing a forty-unit amount, that the turning of arbor 52 a complete rotation causes the dial 52' thereon to indicate 15 one hundred units, and that the relative proportions of the gear and pinion in association with the five-arm star-wheel of that magazine is such that a complete rotation of the star-wheel will give two complete 20 rotations of the arbor, then five forty-unit balls successively moving upwardly in the guideway will cause registration of two hundred units; and assuming that the magazine next beyond is of twenty-unit value, 25 then the relative proportions of the parts would be such that successive movement of five twenty-unit balls would give one complete rotation to the arbor and cause registration of one hundred units. Moreover, 30 the arbor 53 at the other side of the machine, for purposes of explanation, may be assumed to pertain to a one-hundred-unit amount, and a ball from the magazine shown on that side of Fig. 1 on engagement 35 with the star-wheel may cause a sufficient turn in the arbor to cause registration of one hundred units by the dial 53'; and the other sets of star-wheels, gears, and pinions on that side would be of such 40 proportions as to cause a sufficient rotary movement of arbor 53 and dial 53' to register the respective amounts to which their magazines pertain.

Adjacent to each of the pinions 50 and 45 51 there is fast on its arbor an annular rack 54, in engagement with which pivoted pawls 55 are held by springs 56, the pawls and springs being carried by a disk 57 fast to the pinion. The arrangement is such that, 50 when a pinion is given rotary motion by a gear in mesh therewith, rotary motion will be imparted to the arbor through the instrumentality of the rack and pawls, and the racks and pawls of the other pinions will 55 permit the arbor to turn without rotating those pinions and the gears in mesh therewith.

The tendency to rotary motion that pinions on an arbor may have as a result of friction during movement of pawls on the racks and rotation of the arbor in the gears will be overcome by contact of the arms of the star-wheels with overthrow devices. Each of these devices comprises an arm 58 pivoted

on the frame of the machine and having at its free end a roller 59, which is held normally in the annular path of movement of the end portions of the star-wheel arms by a spring 60. When a star-wheel is given a turning movement by an upwardly-moving ball in its guideway, the roller 59 is moved by contact of a star-wheel arm therewith so that the arm can pass, and then it is returned quickly to normal position where it will be contacted by the next arm of the wheel and further rotary movement from frictional or momentum influence prevented. It will be seen also that the overthrow device is so disposed that it will prevent reverse movements of the parts with which it is associated. No more than one gear 48 is given rotary movement at a time in a single machine, because of the diverse arrangement of the teeth of the several chainbelts previously explained; and, therefore, 8 there will be no tendency to give rotary motion to more than one pinion and arbor of the machine at one time, whereby under registration is avoided.

In order that, when the dial 52' on the 9 arbor 52, which may be considered as pertaining to the lowest decimal place of the series of digits displayed by the dials, has registered the greatest amount of which it is capable, that amount may be caused to 91 be registered on the dial 53' of the next arbor on the turning of dial 52' to zero position, the arbor 52 has fast thereon a tooth or other projection 61, which may be carried by a disk 62 secured to the arbor. The 10 tooth 61 is so positioned that it will engage a tooth of and turn a pinion 63 loose on arbor 53 at the time the dial 52' is moved from its highest indicating position to zero. Rotary movement is imparted to arbor 53 10 by pinion 63 through the instrumentality of pawls 64 thereon kept by springs 65 in engagement with an annular rack 66 fast on the arbor. The pinion 63 being loose on its arbor, the pawl and rack arrangement permits the arbor to turn independently thereof when rotary motion is imparted thereto by a pinion 51.

In order to prevent the pinion 63 from being turned otherwise than by engagement 11 therewith of the tooth 61, as by friction between it and the arbor 53, brake bands or rings 67 and 68, respectively, are secured to the disk 62 and the gear 63. A shoe, having a friction-sole 69 in contact with ring 111 68 and an anti-friction roller 69' in contact with ring 67, is carried by a standard 70, which may be pivoted on a frame member of the machine as shown, or which may be of spring material; in either case so that the shoe may be capable of slight movement in order that it may adjust itself to contact with both rings and be held in such con-

tact by oppositely-exerting pressure of the rings themselves. Ring 67 is reduced in thickness for a portion of exterior periphery, as between the places $p-p$, Fig. 9, 5 where the roller 69' contacts with the shoe during the period that the tooth 61 is in engagement with a tooth of and is turning pinion 63, so that the pressure of the sole on the ring 68 is lessened during that 10 period and the pinion left more free to turn.

After the dial 53' has registered the greatest amount that it is capable of indicating and during movement of the dial to zero 15 position, the arbor 53 imparts registering movement, through the instrumentality of a disk 71 fast thereon and a tooth 72 on the disk, to a pinion 73 and a dial 74' on a shaft 74, this dial pertaining to the next 20 greater decimal place of the series of digits indicated by the dials. Overthrow of the dial 74' is prevented by a brake-shoe 75 in frictional contact with brake bands or rings 76 and 77 carried, respectively, by the disk 25 71 and the pinion 73; and either ring 76 and 77, or both of them, may be reduced in thickness at its exterior periphery, as between the places $q-q$ shown in ring 77, Fig. 9, where the ring contacts with the 30 shoe during the period that the tooth 72 is in engagement with a tooth of and is turning pinion 73, so that the pressure of the shoe on the rings is lessened during that period and the pinion left more free to turn. 35 In the series there may be other dials, as those designated by 78' and 79' carried by shafts 78 and 79, to the number of decimal places that the demands on the machine may require to be shown, and movement 40 may be imparted to and retarded in those dials by parts similar to those last explained.

While the primary machine shown by Fig. 1 has been referred to in describing 45 the registering mechanism, it is to be understood that similar registering mechanisms are embodied in other primary machines and in the grand-totalizer machine. The registering mechanism of the grand-totalizer machine in its essential characteristics is like that of a primary machine, except 50 that it is unnecessary to include therein the circuit-closer, unless it is desired to have the totalizer cause actuation in still another 55 machine.

Having thus described my invention, what I claim as new, and desire to secure by Letters Patent, is—

1. In a register, a magazine arranged to hold amount-representing elements, a guideway having a discharge end terminating in said magazine and having a receiving end, means whereby said elements are delivered in series from said magazine to the receiving end of said guideway, a device whereby 65 said elements are moved individually through said guideway from the receiving end to the discharge end and returned to said magazine, and a register-actuating device arranged to be actuated by said elements during their traverse of said guideway.

2. In a register, a magazine arranged to hold amount-representing elements, a hopper, means whereby said elements are delivered individually from said magazine to said hopper, a chute arranged to receive said elements in series from said hopper, a guideway having a receiving end to which said chute delivers said elements and having a discharge end terminating in said magazine, a device whereby said elements are moved individually through said guideway from the receiving end to the discharge end and returned to said magazine, and a 80 register-actuating device arranged to be actuated by said elements during their traverse of said guideway.

3. In a register, a magazine arranged to hold amount-representing elements, a channel into which said elements pass from said magazine, a device whereby said elements are held in said channel and individually released therefrom, a hopper receiving said elements from said channel, a 90 guideway receiving said elements from said hopper, a belt associated with said guideway, devices on which said belt is mounted and by which it is actuated, a part on said belt arranged to move said elements individually through said guideway, and a 100 register-actuating device arranged to be actuated by said elements during their traverse of said guideway.

In testimony whereof I affix my signature 105 in presence of two witnesses.

HENRY A. HENTRICH.
